UNITED STATES PATENT OFFICE.

CHARLES T. WAGNER, OF COLLEGE POINT, NEW YORK.

DESIGN FOR QUILTING.

SPECIFICATION forming part of Design No. 18,415, dated June 26, 1888.

Application filed January 31, 1888. Serial No. 262,590. Term of patent 7 years.

To all whom it may concern:

Be it known that I, CHARLES T. WAGNER, of College Point, Queens county, State of New York, have originated and produced a new Design for Quilting, of which the following is a specification.

My design relates to quiltings which are manufactured for linings for skirts, for garments, and for bed-coverings.

This design consists of a number of lines composed, severally, of an obliquely-extending line, a semicircle at the end of said line, a reverse oblique line extending from the semicircle, a reverse semicircle at the end of the last-mentioned oblique line, then an oblique line forming a repetition of the oblique line first mentioned, and so on.

In the accompanying drawing I have represented a piece of quilting ornamented with my design.

The lines which compose my design are grouped together in pairs, $A' A^2$ and $A^3 A^4$, which are reversed and so arranged that the oblique lines or portions of each shall intersect those of the other. Each pair of these lines, reversed and intersected as described, are so disposed that the figures produced by their intersection will be opposite the spaces between the corresponding figures produced by the intersection of adjacent pairs of the lines.

I will describe one of the lines in detail. a' designates an oblique line or ogee curve; a^2 , a semicircle extending from one end of the ogee curve.

a^3 is an oblique line or ogee curve extending from the other end of the semicircle a^2 and in the reverse direction to the ogee curve a' .

a^4 is a semicircle extending from the ogee curve a^3 . From the other end of this semicircle extends a repetition of the oblique line or ogee curve a' first mentioned.

It will be seen that the oblique lines or ogee curves a' of each pair of lines $A' A^2$ or $A^3 A^4$ intersect, that the semicircles a^2 of each pair of lines are opposite to each other, that the oblique lines or ogee curves a^3 of the lines intersect, and that the semicircles a^4 are opposite each other.

It will be observed that the oblique lines or ogee curves are of such character that the semicircles a^2 are much closer together than the semicircles a^4 . As a result of the intersection of the lines described, there are rows of large figures and intermediate small figures. The lines are so disposed that the small figures produced by the intersection of the pairs of lines $A' A^2$ will be opposite the large figures produced by the pairs of lines $A^3 A^4$, and, conversely, the large figures produced by the pairs of lines $A^3 A^4$ will be opposite the small figures produced by the pairs of lines $A' A^2$.

What I claim as new, and desire to secure by Letters Patent, is—

The design for quilting, consisting in pairs of reversed and intersecting lines severally composed of an oblique line or ogee curve, then a semicircle, then a reversed oblique line or ogee curve, then a reversed semicircle, and then a repetition of the first oblique line or ogee curve, and so on, substantially as shown and described.

CHAS. T. WAGNER.
